UNITED STATES PATENT OFFICE.

WILLIAM M. DAVIDSON, OF ST. LOUIS, MISSOURI, ASSIGNOR TO WILLIAMS PATENT CRUSHER AND PULVERIZER COMPANY, OF ST. LOUIS, MISSOURI, A CORPORATION OF MISSOURI.

CAGE-PARTITION PLATE FOR CRUSHERS.

Application filed September 11, 1922. Serial No. 587,433.

To all whom it may concern:

Be it known that I, WILLIAM M. DAVIDSON, a citizen of the United States, residing at St. Louis, State of Missouri, have invented 5 certain new and useful Improvements in Cage-Partition Plates for Crushers, of which the following is a specification.

This invention relates to certain new and 10 useful improvements in cage partition plates for crushers. The peculiarities of which will be hereinafter fully described and claimed.

The main object of my invention is to provide partitions for the cage of a crusher or like 15 machine having rotary pivoted hammers, which partitions will divide up the length of the cage into compartments of suitable length so that mats of tangled or intertwined material, such as steel turnings, delivered to 20 the hopper, will be held back and torn apart by the hammers before such material can enter said compartments, and will be prevented from matting together again as the material is further reduced on the cage; and 25 secondly, to secure such plates at adjustable positions on the cage.

In the accompanying drawing on which like reference numerals indicate corresponding parts, Fig. 1 represents a sectional elevation across the shaft of a crusher embodying 30 my invention; Fig. 2, a plan view of the machine shown in Fig. 1 with the cover removed, the discs in section and partly broken away to show the cage below; Fig. 3, a detail enlarged view of my plate partition; and 35 Fig. 4, a sectional view on the line 2—2 of Fig. 3.

The numeral 3 designates the casing of a suitable crusher having a rotor shaft 4 mounted therein and carrying hammer 40 mounts in the form of discs 5 supporting hammer rods 6 on which are pivoted suitable rotary hammers 7, the outer ends of which operate in a cylindrical plane of the hammer circle 8. The casing has a hopper 9, the lower end of which preferably has a breaker plate 10 adjacent to a cage of bars 11 with alternating openings, or other form of cage,—and extending from the breaker 45 plate to the rear end of the cage which is preferably near the horizontal plane through the axis of the rotor.

Secured to the cage or otherwise mounted,

is a partition, or plurality of partitions 12, extending from the front end of the cage 55 near the bottom of the hopper, preferably to the rear end of the cage or otherwise, so as to divide the length of the cage into compartments. These partitions are preferably 60 in the form of smooth arcuate plates located in planes parallel to the planes of revolution of the hammers, and extending from the cage inward toward the discs lying in the same plane, and having their inner edge preferably adjacent to the outer edge of the 65 respective discs. These plates thus extend within the cylindrical planes of the hammer circle, and the hammers rotate in the compartments thus formed. The front edge 13 of each partition plate is adjacent to the 70 lower end of the hopper and the front end of the cage, and is substantially radial to the axis of the shaft so as to check mats of tangled material delivered from the hopper till they can be torn apart by the hammers and be further reduced on the cage.

Suitable means to secure said plates in 75 position are employed,—such as bolts 14 the heads of which engage matching openings near the outer edge of the respective plate 80 and pass outward through the openings of the cage and have a washer 15 and nut on each bolt by which it firmly holds the plate in position against the cage in any position lengthwise of the cage to which it may 85 be adjusted, in order to vary the size of the compartment. Thus when the plate is half inch in thickness a half inch bolt with a flattened head as shown in Fig. 4 may be 90 used, and avoids any lateral projection from the plate. On the outer edge of each plate is preferably formed a projecting lug or lugs 16 adapted to enter adjacent openings in the cage and resist the pressure of material against the front edge 13, while the 95 bolts hold the plate firmly against the cage substantially as shown.

I claim:

1. A crusher comprising a shaft, discs on 100 said shaft, rotary hammers mounted on said discs, a cage, a plurality of smooth arcuate plate partitions disposed in planes between the planes of revolution of adjacent hammers and extending from said cage inward closely adjacent to the edge of adjacent 105 discs and from the front of said cage sub-

stantially to the rear end thereof, and means to secure said partitions at variable distances apart on said cage.

2. A crusher comprising rotary hammers, 5 a cage having openings, smooth arcuate partitions disposed parallel to the planes of revolution of said hammers and having outwardly projecting lugs forming shoulders engaging adjacent openings in said cage; and 10 means to secure said partitions to said cage.

3. A crusher comprising rotary hammers, a cage having openings, smooth arcuate plates forming partitions disposed parallel to the planes of revolution of said hammers

and extending inside the cylindrical plane of 15 the hammer circle, and means to fasten said plates,—said means consisting of bolts of a diameter substantially the thickness of said plates and having flattened heads and mounted in matching openings in the plates 20 near the outer edge thereof so as to project through the adjacent openings of said cage and adapted to be secured outside of the cage, substantially as described.

In testimony whereof I have affixed my 25 signature.

WILLIAM M. DAVIDSON.
